CHARLES B. KELLER, OF TIPTON, MISSOURI, ASSIGNEE OF ONE-HALF TO W. E. QUIGLEY, OF TIPTON, MISSOURI.

TOOL-HANDLE.

1,075,108.

Specification of Letters Patent.

Patented Oct. 7, 1913.

Application filed March 8, 1911. Serial No. 613,122.

To all whom it may concern:

Be it known that I, CHARLES B. KELLER, a citizen of the United States, residing at Tipton, in the county of Moniteau and State of Missouri, have invented new and useful Improvements in Tool-Handles, of which the following is a specification.

This invention relates to tool handles and the object of the invention is the provision of means whereby a tool may be readily provided with a handle of such construction that it may be conveniently and expeditiously disconnected for connection with another tool.

15 A further object of the invention is the provision of a tool handle composed of a plurality of sections which, when assembled, form a complete handle which is adapted to be wedged into a tool head by 20 means of coacting parts and which can be attached to any type of tool having a head aperture formed to receive the same.

25 Further objects of the invention will appear as the following specific description is read in connection with the accompanying drawings, which form a part of this application, and in which:—

30 Figure 1 is a side elevation. Fig. 2 is a longitudinal section. Fig. 3 is a perspective view of the attaching head. Fig. 4 is a bottom end view of Fig. 3.

Referring more particularly to the drawings 1 represents the handle proper which is provided with a central longitudinal bore 2 35 and a concentric recess 3 in one end adapted to receive a rod 4 and a concentric boss 5 carried by the knob 6. The rod is rigidly connected to the knob 6 and passes through the bore 2 and the boss 5 seats in the concentric recess 3, a ferrule 7 surrounding the joint between the knob 6 and the main handle section 1. The knob 6 and the handle 1 are both reduced to permit the ferrule to seat flush with the outside thereof and the opposite end of 45 the handle is also reduced, as shown at 8, to receive a ferrule 9 which covers the joint between the section 1 and the attaching head 10. The outer end of the handle section 1, adjacent the reduced portion 8, is 50 provided with a longitudinal wedge-shaped projection 11 which is adapted to enter a

similarly formed socket 12 formed in the attaching head 10. The attaching head is also provided with a concentric bore 13 through which the rod 4 is adapted to pass and the outer end thereof is provided with a projection 14 which is longitudinally recessed, at 15, and the walls of the said recess are grooved, as at 16, so as to provide spring fingers 17. The attaching head flares outwardly from its connection with the handle section 1 to a point where the projection 14 extends therefrom where it is reduced to form a shoulder 18 recessed at 19 to receive a wedge-shaped flange 20 upon the tool head 21.

This tool head is provided with the usual handle receiving socket or aperture 22 into which the projection 14, with its spring fingers 17, is adapted to enter. A cap 23 seats over the aperture at the outer end of the tube and is provided with a wedge-shaped projection 24 and a longitudinally threaded aperture adapted to receive the threaded end of the rod 4.

In assembling the device the rod is passed through the handle section 1 until the boss lies in the concentric recess and the handle section 1 is then connected with the attaching head 10 by placing the wedge-shaped projection 11 in the socket 12 and putting the projection 14 into the socket 22 of the tool. The cap with its wedge projection is then inserted in between the spring fingers and the rod 4 threaded therein by turning the knob 6. This latter action not only pulls the wedge 24 into operative engagement with the fingers and forces them against the walls of the aperture or socket 22 but at the same time causes the wedge 11 to tightly engage the walls of the socket 12. The tool may be readily disconnected from the attaching head by simply removing the cap, the fingers 17 springing back to normal position where the wedge is released therefrom.

Having thus described the invention, what I claim as new is:—

In combination with a tool having an opening therein, a handle comprising an attaching head formed with a projection thereon, said projection being provided

with spaced parallel grooves centrally split to form spring fingers, said projection being provided with a recess therein, a wedge member arranged in said recess and having a flange for engagement with the end of the projection and the outer face of the tool adjacent the opening, and a rod passed through said handle and screwed into the

wedge member substantially as and for the purpose described.

In testimony whereof I affix my signature in presence of two witnesses.

CHARLES B. KELLER.
